UNITED STATES PATENT OFFICE.

WINFRED T. POWELL, OF ROCHESTER, NEW YORK, ASSIGNOR TO THE STROMBERG-CARLSON TELEPHONE MANUFACTURING COMPANY, OF ROCHESTER, NEW YORK, A CORPORATION OF NEW YORK.

AUTOMATIC TELEPHONE SYSTEM.

Refiled for abandoned application Serial No. 516,926, filed November 22, 1921. This application filed August 4, 1926. Serial No. 127,094.

This application is a refile for abandoned application, Serial No. 516,926, filed November 22, 1921.

This invention relates to telephone systems and more particularly to telephone systems employing automatic switches in completing telephone connections.

In some installations of automatic systems a switch known as the Keith type of line switch is employed. This switch is described on pages 38 to 45 inclusive and 55 to 57 inclusive of "Automatic Telephony" by Smith & Campbell, first edition. This type of switch is also well known in the art so that it is not necessary to describe it in detail. In such systems employing the Keith line switch it was customary to provide such a line switch for each subscriber's line, and the purpose of the present invention is to provide circuits whereby one line switch with the addition of several springs will serve to extend two subscribers' lines to idle trunk circuits, in other words it is the purpose of this invention to provide circuits whereby a non-numerical switch will serve the purpose of connecting two subscribers' lines to idle trunks, said non-numerical switch being of that type in which common operating means operates a plurality of line switches.

The drawings with Fig. 2 below Fig. 1 diagrammatically represent a portion of a telephone system incorporating the present invention. The portion of the drawing at the left of the dotted line in Fig. 1 represents the primary line switch which serves to connect the lines of the subscribers A and B to idle trunks, while the master switch mechanism of this primary line switch is shown at the left of the dotted line in Fig. 2. The portion of the drawings of Fig. 1 included between the vertical dotted lines represents two secondary line switches, one of which is referred to as the odd secondary line switch, and the other is referred to as the even secondary line switch, although it will be understood that there is common operating mechanism for operating both of these secondary line switches. A portion of this common operating mechanism is dia- grammatically represented at the right of the dotted line in Fig. 2. It will be understood that the secondary line switches seize trunks leading to numerical switches such as selectors and connectors depending upon 55 the size of the system in which this invention is employed.

For purposes of this description it will first be assumed that the primary and secondary master switches have pre-selected 60 idle primary and secondary trunks for use. Under these conditions, when the calling subscriber at A removes his receiver from its switch hook, a circuit is closed for the slow releasing line relay 5 from grounded battery, through the lower winding of this relay and contacts 6 and 7, over the upper side of the calling line and through the substation circuits in series, over the lower side of the calling line through contacts 8, 9 and 10 to ground. The line relay 5 is thus caused to attract its armature and thereby close a circuit from ground through the so-called pull-down coil 11, which operates the armature 12 and this in turn causes the 65 plunger (not shown) to force the sets of spring contacts 13, 14, 15, 16, 17 and 18 into engagement. The calling line will, therefore, be extended through contacts 19 and 70 winding of the slow releasing relay 20 of 75 the odd secondary line switch to grounded battery and through contacts 21 to ground. The relay 20 is actuated in this circuit and closes an operating circuit from ground through the pull-down coil 22 of the odd sec- 80 ondary line switch, conductor 23, armature and back contact of locking magnet 24 to grounded battery. When coil 22 actuates its armature 25 it opens the circuit of the slow 85 releasing relay 20 and closes the contacts 26, 27 and 28 by the operation of its plunger (not shown). As soon as relay 20 is operated it closes a holding circuit for the primary line switch from ground, lowermost 90 armature and front contact of relay 20, 95 spring contacts 13, conductor 29, contacts 30 and the so-called bridge cut-off relay of the line switch to grounded battery.

When contacts 26 and 27 have been operated the calling line A is extended through 100

both windings in series of the relay 32 of the first numerical switch to ground and grounded battery respectively.

Relay 32 when operated actuates the slow releasing relay 33 which places the holding ground on conductor 34, thereby completing the holding circuit through contacts 28 and coil 35 of the secondary line switch to grounded battery. It will also be noted that the coil 31 of the primary line switch is now held operated in multiple with the holding conductor 34, so that the primary and secondary line switches will be maintained operated until the time of release. The relay 32 corresponds to line relay L. R. in the circuit of Fig. 53 on page 57 in the mentioned "Automatic Telephony" by Smith & Campbell. It is not necessary to describe the operation of such a numerical switch but it is sufficient to know that when a trunk leading to such a selector or connector switch is seized, a relay such as 32 actuates the slow releasing relay 33 to complete a holding circuit for the non-numerical switches of the connection, and that at the time of disestablishing the connection, the relay 32 deenergizes and shortly afterwards the slow releasing relay 33 deenergizes to open the mentioned holding circuit, to permit the release of the operated primary and secondary line switches. This is effected by the deenergization of the holding coil 31 of the primary line switch and the deenergization of the holding coil 35 of the odd secondary line switch. When these holding coils deenergize mechanism not shown but well known in this art, removes the plungers from the contact banks permitting the contacts such as 13, 14, 15, 16, 17, 18, 26, 27 and 28 to separate.

In the first part of this description, it was assumed that the master switches such as those disclosed in Fig. 2 had already pre-selected an idle trunk circuit for use. The operation of these master switches by which they select idle trunks will now be described. When contacts 13 of the primary line switch were closed by the operation of the plunger of this switch and when relay 20 of the seized secondary selector is operated, ground potential is applied to conductor 36 indicating that this trunk circuit is engaged. At this time a circuit is closed over conductor 36 through the contacts and wiper 37 of the master switch, left hand winding of start relay 38 to grounded battery. With relay 38 operated, an actuating circuit is closed for the locking magnet 39, extending from grounded battery, winding of this magnet, front contact and armature of relay 38, right hand winding of the supervisory relay 40 to ground. Locking magnet 39 attracts its armatures and thereby permits the spring (not shown) to advance the plunger operating arm and with it the

plungers of idle line switches of this group (not shown) to the next trunk circuit. In the event that one or both of the next pair of trunk circuits is engaged, the test contacts 42 and 43 will be characterized by the presence of ground potential so that start relay 38 and consequently the lock magnet will be still operated and the spring will advance the plunger operating arm into position before the next pair of trunk circuits. 75

At the left of Fig. 2 there will be seen two insulated projections designated 44 and 45. These projections are actuated by the plunger operating arm and are so positioned that when this arm has been moved to its last position under the control of the mentioned spring, projection 44 will close contacts 46 whereupon the trip magnet 47 will be operated in a circuit, traceable from grounded battery, winding of this magnet, contacts 46, front contact and armature of relay 38, low resistance winding of the supervisory relay 40 to ground. The trip magnet 47 will attract its armature 48 which will be held in this position by latch 49. This will close an operating circuit for the solenoid 41 which then actuates the plunger operating arm to move it into its farthest position in the other direction at which time the projection 45 will cause latch 49 to release the armature 48. From this it will be seen that the solenoid actuates the plunger operating arm in one direction and also places the spring under tension which tends to move the plunger arm in the opposite direction. The lamp 50 is an alarm signal which indicates to the attendant that some portion of the line switch equipment has failed to operate properly. 95

In the event that it is the subscriber at B instead of the subscriber at A that initiates a call, the line relay 5 will be energized in a circuit including the upper winding of the line relay 5, whereupon the primary line switch will be operated in the manner already described to close its contact springs 13 to 18 inclusive. When this takes place the relay 60 of the even secondary line switch will be energized over the two sides of the calling line in series and will effect the operation of the even secondary line switch to seize a trunk circuit leading to a selector or connector depending upon the system in which it is used. It will be understood that the relay 20 of the odd secondary line switch will not be operated at this time since its operating circuit will be open due to the fact that the receiver at the substation A is on its switch hook. 115

Let it be supposed that the subscriber at B initiates a call while the subscriber at A is calling, the primary line switch will, therefore, be already actuated in the manner already described, so that contact springs 17 and 18 will be closed to complete a circuit 125

for the slow releasing relay 60 of the even secondary line switch which will then function to extend the calling line from substation B to an idle secondary trunk leading 5 to a selector or connector switch.

It will be seen that the primary line switch of Fig. 1 will be held operated while 10 a connection is maintained from either of the substations A or B. If it is the calling substation A that is maintaining the connection the primary line switch will be held operated over conductor 36, and if it is substation B that is maintaining the connection, the primary line switch will be held 15 operated over conductor 62.

In case the line terminating at substation A is seized as a called line as soon as the connector switch (not shown) is stopped with its brushes in engagement with the terminals 20 of this line and after the test thereof, then ground potential is applied at this connector switch and is extended to conductor 29, thereby forming a circuit including the upper winding of line relay 5 to grounded battery. The line relay is energized in this circuit and the primary line switch operates in the manner already described to close contact springs 13 to 18 inclusive, whereupon the circuit extending from ground at the 25 connector switch will be completed through the contact 13 and the winding of the cut-off coil 35 of the odd secondary line switch. This coil 35 is effective to open the springs 19 and 21 to prevent the operation of the relay 20 but it does not operate the plunger to extend the primary trunk to a selector or connector switch. In the event that substation B had been called, the primary line switch would be operated in a similar manner but in this instance the cut-off coil of the 30 even secondary line switch would disable its relay 60 to prevent the primary trunk from being extended to a selector or connector switch.

It will thus be seen that circuit arrangements have been provided whereby one non-numerical switch of the plunger type is made individual to two subscribers' lines. It will be understood, of course, that there may be 40 variations in the circuit arrangements described by the appended claims without departing from the spirit of the present invention.

What is claimed is:—

1. In a telephone system, a plurality of telephone lines, a plurality of trunks, a plurality of non-numerical switches, and motor mechanism common to said switches, each switch being individual to a group of several lines and operating on the initiation of a call over one of said lines to extend the lines of said group to idle trunks.

2. In a telephone system, a plurality of progressively movable non-numerical switches, 65 operating means common to said switches,

a pair of telephone lines terminating in each switch, a plurality of trunk circuits each terminating in each of said switches, and means operated by the initiation of a call on one of the telephone lines of a pair for extending 70 said last mentioned telephone line to a trunk circuit.

3. In a telephone system, a plurality of non-numerical switches having spring contacts and actuating means for forcing said spring contacts into engagement, operating mechanism common to the actuating means of said switches, two telephone lines and a plurality of trunk circuits terminating in the spring contacts of each switch, and means responsive to the initiation of a call on one of said telephone lines for causing the actuating means of its non-numerical switch to extend said calling line to a trunk circuit. 80

4. In a telephone system, a plurality of progressively movable non-numerical switches, contact springs and a contact spring-closing member for each non-numerical switch, operating mechanism common to said members, a pair of telephone lines and pairs of trunk circuits terminating in the spring contacts of each of said switches, and means responsive to the initiation of a call on one of said telephone lines for actuating the related contact spring operating member to cause 90 the contact springs of the calling line and an idle trunk to be brought into engagement. 95

5. In a telephone system, a plurality of non-numerical switches, contact springs and a contact-spring-closing member for each non-numerical switch, operating mechanism common to said members, a pair of telephone lines and pairs of trunk circuits terminating in the spring contacts of each of said switches, and means responsive to the initiation of a call on one of said telephone lines for actuating the related contact spring operating member to cause the contact springs of the calling line and an idle trunk to be 100 brought into engagement. 105

6. In a telephone system, a plurality of line switches, substantially passive contacts for each of said switches, two telephone lines and a plurality of trunks terminating in each line switch, actuating mechanism for the passive contacts of each line switch effective on the initiation of a call on either of its lines to connect said line to a trunk circuit, and operating means common to the actuating mechanisms of said line switches. 110 115

7. In a telephone system, a plurality of primary line switches, terminal contacts and actuating means for the same in each switch, operating mechanism common to the actuating means of said switches, a pair of telephone lines extending to certain of the terminal contacts of each switch, trunk circuits arranged in pairs and multiply connected to others of said terminal contacts, a secondary line switch for each of said trunks, second- 120 125 130

ary trunks terminating in each of said secondary line switches, means effective on the initiation of a call on either of the telephone lines of a pair for causing the actuating means of the related line switch to seize a pair of trunks leading to idle secondary line switches, and means for automatically operating the secondary line switch now connected to the calling line to extend said line to an idle secondary trunk.

8. In a telephone system, a plurality of primary line switches, terminal contacts and actuating means for the same in each switch, operating mechanism common to the actuating means of said switches, a pair of telephone lines extending to certain of the terminal contacts of each switch, trunk circuits arranged in pairs and multiply connected to others of said terminal contacts, a secondary line switch for each of said trunks, common operating means for said secondary line switches, secondary trunks terminating in each of said secondary line switches, means effective on the initiation of a call on either of the telephone lines of a pair for causing the actuating means of the related line switch to seize a pair of trunks leading to idle secondary line switches, and means for automatically operating the secondary line switch now connected to the calling line to extend said line to an idle secondary trunk.

9. In a telephone system, telephone lines, a plurality of trunks, a line switch individual to several of said lines for extending said lines to separate idle trunks, means common to several line switches for testing said trunks, and means to extend said selected trunks to wanted telephone lines.

10. In a telephone system, telephone lines, a plurality of trunks, line switches individual to several of said lines for extending said lines to separate selected trunks on the initiation of a call, and means for selecting the trunks ahead of the calls.

11. In a telephone system, telephone lines,

a plurality of primary trunks, a line switch individual to several of said lines for extending said lines to separate idle primary trunks, means for selecting primary trunks ahead of the calls, a secondary line switch for each primary trunk, secondary trunks terminating in said secondary line switches for extending calling lines and primary trunks on the initiation of calls, and means for selecting idle secondary trunks ahead of the calls.

12. In a telephone system, a plurality of line switches of the plunger type, two telephone lines and a plurality of trunks terminating in each line switch, and means responsive to the initiation of a call on one of said telephone lines for causing the line switch of said line to extend it to an idle trunk.

13. In a telephone system, a plurality of telephone lines, a plurality of trunk circuits, a line switch individual to each pair of telephone lines and having a plunger for interconnecting the calling line and a pre-selected trunk, and a master switch for positioning the plungers of idle line switches before idle trunks.

14. In a telephone system, a plurality of telephone lines, a plurality of primary trunks, a line switch of the plunger type individual to each pair of telephone lines, a master switch common to said line switches and operating to position the plungers of idle line switches in a position to seize idle trunks when one of their related telephone lines initiates a call, secondary line switches of the plunger type and master switch mechanism for operating the plungers of said secondary line switches, one of said secondary line switches being individual to each primary trunk, and secondary trunk circuits terminating in said secondary line switches.

In witness whereof, I hereunto subscribe my name this 3rd day of August, A. D. 1926.

WINFRED T. POWELL.
